COMBINED LAMP AND COLOR WHEEL

Bernard Fineman, 1802 N. 77th St., and Isadore Fineman,
1234 Hale St., both of Philadelphia, Pa.

Original application Aug. 5, 1963, Ser. No. 76,094, now
Design Patent No. 199,325, dated Oct. 6, 1964. Di-
vided and this application July 13, 1964, Ser. No. 80,820

Term of patent 14 years

(Cl. D48—20)

FIG. 1

FIG. 3

FIG. 2

FIG. 1 is a front elevational view of a combined lamp and color wheel showing our new design;

FIG. 2 is an elevational view taken from one side thereof, the conventional electric cord being broken away for convenience of illustration; and

FIG. 3 is a top plan view thereof.

This application is a division of our co-pending design application Serial No. 76,094, filed August 5, 1963, now Design Patent No. 199,325, issued October 6, 1964.

We claim:

The ornamental design for a combined lamp and color wheel, substantially as shown and described.
